ORIGIN AND HISTORY OF THE NEW PLANT

The new plant of the present invention comprises a new and distinct cultivar of Chrysanthemum plant which is a cross of unknown *Chrysanthemum morifolium* parents. The new and distinct cultivar was a seedling resulting from the open pollination among groups of chrysanthemum cultivars maintained under the control of the inventor for breeding purposes. The new and distinct cultivar was discovered in a greenhouse in Ter Aar, Holland in 1986. The invention has been asexually reproduced by cuttings in greenhouses at Ter Aar, Holland. The new cultivar has been found to retain its distinctive characteristics through successive propagations.

SUMMARY OF THE NEW PLANT

The present invention is a new and distinct variety of Chrysanthemum of a medium sized bloom and pink color.

BRIEF DESCRIPTION OF THE DRAWINGS

The present new and distinct chrysanthemum cultivar is shown in the accompanying drawings, the color being as nearly true as possible with color photographs of this type.

Sheet 1 shows the full bloom of the new cultivar; Sheet 2, top, shows various stages of bloom of the new cultivar; and

Sheet 2, bottom, shows the foliage and petiole of the new cultivar.

DESCRIPTION OF THE INVENTION

This new variety of chrysanthemum is of the botanical classification *Chrysanthemum morifolium*, and is named Reagan. When grown in the vicinity of Ter Aar,

2

Holland, it has a response time of approximately 7½ weeks. This new variety produces medium sized pink blooms with a yellow green center having a 4 week performance (i.e., a vase life of 24-28 days). This new variety of chrysanthemum has been found to retain its distinctive characteristics throughout successive propagations and may be planted under greenhouse conditions in Holland between weeks fifty and thirty-five (i.e., between December 1 and August 30). Pest resistance, disease resistance and frost tolerance are unknown.

The following is a description of the plant and characteristics (color designations are from RHS Color Chart) that distinguish it over related known varieties and its antecedents:

Botanical classification: *Chrysanthemum morifolium*.

Bud:

Size.—Medium (cross section $\pm$ 1.0 cm, height $\pm$ 0.7 cm).

Form.—Round and flat.

Outside color.—Grape-purple 186D but paler.

Bloom:

Size.—Medium.

Fully expanded.—6½-7 cm.

Borne.—Upper portion, single flower per peduncle; lower portion, plural flowers per peduncle.

Stems.—Strong, thick.

Forms.—Single (daisy).

Performance.—Very good 24-28 days (18°-20° C.).

Color:

Center of flower.—Immature: yellow green 151 C.
Mature: yellow green 154 A.

Base of petals.—Purple 75 B.

Inside of petals.—Purple 75 B.

Reverse of petals.—Red purple 69 A but paler.

Outer petals.—Red purple 75 B.

Tonality from a distance.—A pale pink daisy with a fresh looking center having little or no pollen.

Discoloration.—Some to red purple 69 D.

Pollen.—Yellow-orange 14A.

Petals:

Texture.—Uppercide smooth, underside smooth.

Number.—24-30 (two rows).

Cross-section.—Flat, two keels.

Arrangements.—Imbricated.

Persistance.—Good. Petals keep straight or reflex somewhat at the edge at the end of blooming.

Fragrance.—Typical Chrysanthemum.

Disc diameter.—1.5 cm.

Reproductive organs:

Stamen.—Yellow, thick, 3 mm in length.

Pollen.—Appears at a late stage of blooming yellow orange in color. 5

Styles.—Green thick.

Length.— ± 5 mm.

Stigmas.—Yellow.

Width.— ± 1 mm.

Ovaries.—Enclosed in calyx.

Plant:

Form.—Spray mum meant for erect culture. Herbageous.

15

Growth.—Strong.

Height.—100-125 cm.

Peduncle.—Near the top ± 14 cm, near the middle ± 24 cm, near the bottom ± 28 cm.

20

Internodes.—3 cm.

Flowering response.—7½ weeks.

Foliage:

Color.—Upperside green 137 A. Underside 137 C.

Size.—Length ± 12 cm. Width ± 9 cm.

Quantity.—22-28.

25

Shape.—Lobed, see photograph.

Texture.—Upperside rough. Underside smooth, slightly hirsute.

Ribs and veins.—Ribs well developed. Veins not so developed.

Edge.—Crenated.

Distinguishing characteristics of the chrysanthemum of the Reagan family are summarized below in the Table. Each of the titled Reagans having a color designation is an induced mutation by irradiation of Reagan. 35
